UNITED STATES PATENT OFFICE.

DAVIS H. DOTTERER, OF PHILADELPHIA, PENNSYLVANIA.

IMPROVEMENT IN LOCKS FOR SLIDING DOORS.

Specification forming part of Letters Patent No. 149,729, dated April 14, 1874; application filed February 21, 1874.

To all whom it may concern:

Be it known that I, DAVIS H. DOTTERER, of Philadelphia, in the county of Philadelphia and State of Pennsylvania, have invented a certain new and useful Improved Self-Acting Sliding Door-Lock for Freight-Cars and other purposes; and I do hereby declare the following to be a full, clear, and exact description of the invention, such as will enable others skilled in the art to which it pertains to make and use it, reference being had to the accompanying drawings, which form part of this specification, in which—

Figure 1 is a front view of the carriage and lock in position for operation. Fig. 2 is an elevation, showing carriage-plate removed, with internal arrangement of parts. Fig. 3 is a side elevation or end view, partly in section.

My invention has for its object to provide a more perfect lock for the doors of freight-cars than any heretofore produced, and to combine with said lock a carriage or rolling support for the door.

The nature of my invention consists, first, of a rolling or wheeled door-carriage, provided with a lock, the bolt of which locks into a notch in the rail; secondly, in the combination, with a lock mechanism, of a plate, having an extension, with a lip or hook passing beneath or embracing the rail below the door, to prevent the latter from being raised for the purpose of obtaining access to the lock; thirdly, in the novel construction of the lock, comprising a pivoted or swiveled latch, locking automatically into a notch in the rail, and a tumbler which retains said latch in place when locked; and, fourthly, in the combination, with a freight-car door and lock, of a rail, having two or more notches, so that the door may be locked when partially opened or entirely closed, all as hereinafter more fully described.

Referring to the accompanying drawing, A is a freight-car door with my improvements applied; and B is the rail upon which said door moves. C is the carriage or support, consisting of a metal plate secured to the lower part of the door, and affording bearings for the rollers E E, which ride upon the rail

B. D is an extension of the plate C, having a lip, d, which passes beneath the lower edge of the rail, and which should be curved so as to form a hook, as shown in dotted lines, to embrace the lower edge of the rail, and thereby prevent the door from being raised or pried up for the purpose of obtaining access to the lock or its latch G. F is the case or box of the lock, securely attached to the inner side of the plate C, and fitting in a recess formed in the door. G is the latch, turning or oscillating on the trunnions g, of which only one is shown in drawings, the corresponding one being on the opposite side of the latch. H is a spring, which serves to keep the latch G pressed down upon the rail, and in the V-shaped notch therein, shown at b, when the door is closed. The tumbler I and key-hub K are in their normal positions when the door is closed, as shown in full lines in the drawing.

To unlock the door a key must be inserted at i, throwing back the tumbler I. The key is then withdrawn from i and inserted at k, turning down the key-hub K upon the latch G, and raising its end out of the V-notch b in the rail. The door is then pushed back, still holding the key-hub K down upon the latch, until the lower end of the latter clears the notch b. To lock the door it is only necessary to slide it to a closed position, the latch at once entering the V-notch, and the tumbler I falling into position automatically.

b' is a notch similar to b, and designed to enable the door to be locked or made fast when slid back a distance sufficient to allow ventilation of the car, while preventing access by thieves.

The improvements herein described may be applied with advantage to other sliding doors besides those of freight-cars, nor do I limit my application of them to the latter.

What I claim as my invention, is—

1. A rolling or wheeled door carriage provided with a lock, the bolt of which locks into a notch in the rail, substantially as shown and described.

2. In combination with a lock mechanism the plate C, having the extension D, and lip or hook d passing beneath or embracing the

rail below the door, so as to prevent it from being pried up or raised for the purpose of obtaining access to the lock.

3. The pivoted or swiveled latch G locking automatically into the notch b in the rail, and held down therein by the tumbler I, substantially as shown and described.

4. In combination with a freight-car door and lock a rail to receive the bolt, having two or more notches, so that the door may be

locked when partially opened or entirely closed, substantially as and for the purpose described.

In testimony that I claim the foregoing I have hereunto set my hand this 17th day of February, 1874.

DAVIS H. DOTTERER.
